a corporation of California

Application February 25, 1952, Serial No. 273,312

7 Claims. (Cl. 16—100)

1

This invention relates to sliding door construction and particularly to a readily adjustable device for positioning and maintaining a sliding door in selected relationship with a door frame.

In sliding door construction, a fixed door frame is constructed with side jambs, head and sill in virtually squared relation. One side jamb is provided normally with a lock means adapted to be cooperable with a lock element carried by the sliding door, and weather strip means may be provided on each of the door frame members to provide a weather-tight seal in cooperation with the sliding door. Sliding doors are manufactured and fabricated with their side members and top and bottom rail members in precise, accurate squared relationship for such a squared door frame. Such a door frame is shipped without glass; the door being glazed on the job site.

Very frequently during handling and shipment, the originally squared door members are jostled or bumped into out-of-squared relationship so that the door members assume a parallelogram relationship wherein opposite members are virtually parallel but contiguous members are not joined at right angles. In wood sliding doors, this problem was readily solved by a carpenter trimming the edges of the door so that they would be in virtually parallel relationship with the several members of the door frame. It is not practical or feasible to attempt to resquare the outer edges of a metal-frame sliding door.

Installation of such an out-of-square metal-framed door in a squared door frame obviously does not afford proper interengaging relationship between the door members and the cooperable door frame members. It is particularly important that the edges of the side members of the door be parallel to the side jambs of the door frame in order that the locking means carried by each may be operable and so that the weather strip means provided between the side members of the door and the side jambs of the frame may properly cooperate to afford a weather-tight seal. Slightly out-of-parallel relationship between the rail members of the door and the head and sill of the frame does not create a serious problem because usually the bottom rail member is supported upon spaced wheel and axle assemblies which ride on a guide track provided on the sill and weather strip means may be conveniently adjusted to the sill. Likewise, the top rail of the door usually extends into a groove in the head of the frame and the weather strip means is normally effective even though the rail may be slightly out of parallel relationship with the head of the frame.

2

Heretofore this problem was crudely solved on metal-framed doors by shimming one of the wheel and axle assemblies carried by the bottom rail of a metal-framed sliding door, thus raising one corner of the door and moving the side parallel members of the door into parallel relationship with the side jambs. The shims were usually secured by suitable screws or by welding and once installed could not be conveniently adjusted. Since the shims could not be secured while the door was in place in the door frame, a door was installed in the frame and removed therefrom several times before the desired adjustment was achieved. Such a method was time-consuming and required additional tools and equipment.

It is therefore the primary object of this invention to provide a device which may be carried by a sliding door and which may be simply and conveniently adjusted to bring side members of an out-of-square door into parallel relation with side jambs of a door frame.

An object of this invention is to design and provide a prefabricated assembly providing an adjustable device which may be easily and readily installed on the bottom rail of a sliding door in place of one of the previously fixed wheel and axle assemblies.

Another object of this invention is to design and provide an adjustable device for sliding doors which is adapted to raise or lower one of the wheel and axle assemblies provided for the door to move side members of the door into parallel relationship with jambs of the frame.

A further object of this invention is to design and provide an adjustable device for sliding doors wherein carrier means for a wheel and axle assembly are pivoted at one end and selectively positionable at the other end by wedge means for raising or lowering the wheel and axle assembly with respect to the door.

Still another object of this invention is to design and provide an adjustable device for sliding doors comprising a mounting bar, a carrier means for a wheel and axle assembly pivotally secured to said mounting bar, and easily accessible and adjustable wedge means between the mounting bar and the carrier means for adjusting the position of the wheel and axle assembly.

Generally speaking, this invention contemplates a simply constructed, easily attachable, adjustable device for sliding doors which is adapted to be substituted for one of the prior fixed wheel and axle assemblies normally carried by a sliding door. The adjustable device may comprise a carrier means for a wheel and axle assembly which is pivotally mounted at one end for movement

about a horizontal transverse axis with respect to the rail and which is adjustably secured at its other end for permitting limited pivotal movement in a vertical direction about said pivotal axis. A wedge shoe extends beneath the latter end of the carrier means and is adapted to be longitudinally advanced and retracted by easily accessible screw means for raising and lowering one corner of a sliding door so as to move the side members of the door into parallel relation with the jambs of a door frame.

Other objects and advantages of this invention will be readily apparent from the following description of the drawings.

In the drawings:

Fig. 1 is a fragmentary side view of a sliding door and a door frame, the view being partly in section to show the mounting of an adjustable device embodying this invention upon the bottom rail of the door, and the door being illustrated in out-of-square relationship to the door frame.

Fig. 2 is an enlarged view of the adjustable device in Fig. 1 secured to the bottom rail of a sliding door.

Fig. 3 is a transverse vertical sectional view taken in the plane indicated by line III—III of Fig. 2.

Fig. 4 is a transverse vertical sectional view taken in the plane indicated by line IV—IV of Fig. 2.

Fig. 5 is a sectional view taken in the plane indicated by line V—V of Fig. 1 of the door and door frame adjacent the top thereof illustrating non-cooperable relationship of an out-of-square door with side jambs of a door frame.

Fig. 6 is a sectional view taken in plane indicated by line VI—VI of Fig. 1.

The drawings show an exemplary illustration of an adjustable device embodying this invention, generally indicated at 10, carried and mounted upon a bottom rail member 11 of a metal-framed sliding glass door generally indicated at 12. The sliding door 12 may comprise in addition to the bottom rail member 11, side members 13 and a top rail member 14, said door members all lying in the same plane and normally fabricated in squared relationship.

The door frame forming the opening to be closed by a sliding door 12 comprises a sill 15 carrying a guide rail 16 for cooperation with wheel and axle assemblies supporting the sliding door. Side jambs 17 are connected across the top by a head member 18, said sill member, side jamb members and head member being illustrated as being in true squared relation.

In the illustration, the door 12 is shown with the door members in slightly out-of-square relation or in the arrangement of a parallelogram. The out-of-square relation is exaggerated in Figs. 1, 5 and 6 for clarity and to show the non-cooperation of a door side member 13 with respect to a side jamb 17 of the door frame. It is apparent from these illustrations that while a weather seal is provided at the lower side portion of the door (Fig. 6) by reception of flange 13a within the weather-stripped groove 17a, this condition does not exist at the top side portion of the door (Fig. 5) where an open space "A" exists between groove 17a and flange 13a. Lifting of the side of the door opposite to the jamb 17, in this example, will move the door side member into parallel relation with the jamb and provide proper cooperation between flange 13a and groove 17a.

This invention contemplates that one of the

wheel and axle assemblies normally carried by the bottom rail of a door be carried or mounted in the adjustable device 10 of this invention. In Fig. 1 a wheel and axle assembly 20 is illustrated as being carried at one end of the bottom rail member 11 in well-known manner. The opposite end of the bottom rail member 11 carries a wheel and axle assembly 21 mounted in the adjustable device 10 of this invention.

10 The device 10 comprises a carrier means 22 for wheel and axle assembly 21, said carrier means including a U section metal member having a transverse wall 23 integrally joining parallel depending side walls 24. The side walls 24 may be provided with aligned ports for providing an axle mounting at 25 for the wheel and axle assembly 21.

15 A mounting bar 26 of elongated flat metal stock may be secured to the top wall 27 of the bottom rail member 11 in any suitable manner as by screws 28 extending through ports 29 adjacent each end of bar 26. At one end, bar 26 may be provided with a depending off-set horizontally extending clip 30 preferably stamped from the metal of the bar to provide a pivotal mounting for one end of carrier means 22 as by partially receiving the adjacent end margin of wall 23 between clip 30 and bar 26.

20 Longitudinally spaced from clip 30 and at approximately the central portion of the mounting bar 26, a depending guide and limit screw or pin 31 is carried by the bar. The screw 31 extends through a port 32 provided in the end portion of transverse wall 23 opposite to the end margin 35 engaged by clip 30. The screw 31 is provided with a head 33 of greater diameter than port 32 so as to limit downward pivotal movement of the carrier means about its pivotal axis. The end of screw 31 threadedly engaged in bar 26 may be peened over or center punched so as to prevent unthreading thereof. It will thus be noted that the carrier means is provided selected limited pivotal movement about a horizontal transverse axis at clip 30 and is held in assembled relation with the mounting bar 26.

25 A wedge shoe or member 35 operably extends between the non-pivoted end margin of transverse wall 23 of the carrier means 22 and the opposed surface of mounting bar 26. The shoe 35 may be of generally hollow construction comprising a base portion 36 adapted to slide along the opposed surface of bar 26 and provided with an open ended slot 37 adapted to slidably receive screw 31 therein for guiding longitudinal movement of the shoe 35. Generally triangular shaped depending spaced walls 38 are integrally joined with base portion 36 and an end wall portion 39. The edges of the triangular shaped walls 38 are adapted to contact as at 40 the adjacent end edge of transverse wall 23.

30 Means for longitudinally advancing and retracting wedge shoe 36 to raise and lower wheel and axle assembly 21 may be provided by a headed screw bolt 42 journably secured at one end to wall 39 as at 43. The screw bolt 42 may be supported by a downwardly extending loop 44 formed in mounting bar 26, said loop having ported spaced depending walls 45 through which the screw bolt 42 extends. Between spaced walls 45 is a nut 46 having threaded engagement with bolt 42.

35 The end wall 41 of the bottom rail member 11 may be provided with an access opening 49 aligned with screw bolt 42 and through which a

suitable tool such as a screw driver may be inserted for cooperative engagement with the notched head of screw bolt 42 for adjustably moving the wedge shoe 36.

The adjustable device 10 is preferably secured to the bottom rail member 11 of a sliding door at the factory although it may be secured thereto on the job if desired. When an out-of-square door 12 is installed in a door frame the device 10 may be readily adjusted to position and maintain the door with its side members in parallel relation to the side jambs of the frame. This may easily be accomplished by turning screw bolt 42 in a selected direction so as to either advance or retract the wedge shoe 36 for wedging engagement between the carrier means 22 and mounting bar 26.

When making the adjustment a suitable tool may be inserted beneath the bottom rail 11 to relieve the adjustable device of the dead load of the sliding door when it is being adjusted. Removal of the inserted tool will place part of the dead load of the sliding door upon the wheel and axle assembly 21. Such load tends to press the wedge shoe 36 outwardly and in so doing, moves the screw bolt 42 outwardly so that tolerance is taken up between the nut 46 and the closely adjacent inner surface of the outer wall 45. The screw bolt 42 is thus frictionally held by the nut in selected position in such a manner that it does not become loose during operation of the door.

It will be readily understood by those skilled in the art that the adjusting device 10 may be mounted on either the top or bottom rail of a sliding door, as for example, when the sliding door is hung from rollers engaging track means carried by a head member of a frame. Likewise, the use of the device is not limited to steel framed sliding glass doors but may be readily secured and applied to wooden sliding door frames.

A sliding door provided with the adjustable device of this invention may be quickly installed at the job site in such a manner that weatherstripping between the side jamb of the frame and the opposed side member of the door will be effective throughout the entire height of the side member of the door. Door locking means are quickly adjustable into cooperative relation.

It is understood that adjustable devices of this invention may be installed adjacent each end of a rail member of a door so as to provide a greater degree of adjustment if desired. The mounting bar of the device may be eliminated and the carrier means supported directly from the rail member.

Various other modifications may be made in the exemplary device of the invention described above and all such modifications and changes coming within the scope of the appended claims are embraced thereby.

I claim:

1. An adjustable roller device for use with a metal-framed sliding door including a hollow rail member having an end wall with an access opening therein; said adjustable device adapted to be carried by the rail member adjacent to the end wall and comprising a mounting bar adapted to be secured to the rail member; an elongated carrier means having a pivotal connection at one end to said mounting bar; a headed member carried by the mounting bar and slidably associated with the carrier means for limiting movement of said carrier means about said pivotal connection; a wheel and axle assembly mounted on said

carrier means; a wedge shoe interposed between the carrier means and the bar and having a wedge face in engagement with said carrier means; and screw means carried by the bar and connected to the wedge shoe for advancing and retracting said shoe, said screw means being adapted to be aligned with the access opening.

2. A device as recited in claim 1, wherein a slot is provided on said shoe cooperable with the headed member carried by the bar for holding the shoe in alignment with the screw means and the carrier means.

3. A device as recited in claim 1, wherein a pair of spaced ported parallel depending walls are integrally formed on said mounting bar for carrying said screw means and a nut is carried by said screw means between said walls.

4. An adjustable roller device for use with a sliding door including a rail member having an access opening therein; said adjustable device being adapted to be carried by the rail member adjacent to the end wall and comprising a mounting bar adapted to be secured to the rail member; an elongated carrier means having a pivotal connection at one end to said mounting bar; means carried by the mounting bar for limiting movement of the carrier means about said pivotal connection; a wheel and axle assembly mounted on said carrier means; a wedge shoe interposed between the carrier means and the bar and having a wedge face in engagement with said carrier means; and screw means carried by the bar and connected to the wedge shoe for advancing and retracting said shoe, said screw means being adapted to be aligned with the access opening.

5. A device for use with a sliding door and in combination with a rail of said door comprising: carrier means adapted to journalably support a wheel and axle assembly; means supported by the rail pivotally mounting one end of said carrier means for movement about a transverse horizontal axis; means supported by the rail and associated with the other end of said carrier means limiting pivotal movement of the carrier means about the pivotal axis; a wedge shoe interposed between the latter end of the carrier means and the rail; and means for advancing and retracting the wedge shoe while in engagement with the carrier means to raise and lower the wheel and axle assembly by pivotal movement of the carrier means about said pivotal axis, said advancing and retracting means including a screw means connected to said wedge shoe and cooperable nut means supported by the rail.

6. A device for use with a sliding door and in combination with a rail of said sliding door for positioning and maintaining side members of said door in parallel relationship with side jambs of a door frame comprising: carrier means adapted to journalably support a wheel and axle assembly; means supported by the rail pivotally mounting one end of said carrier means for movement about a transverse horizontal axis; means associated with the other end of said carrier means limiting pivotal movement of the carrier means about the pivotal axis; a wedge shoe interposed between the latter end of the carrier means and the rail; and means for advancing and retracting the wedge shoe while in engagement with the carrier means to raise and lower the wheel and axle assembly by pivotal movement of the carrier means about said pivotal axis.

7. A device for use on a sliding door compris-

7
ing: carrier means adapted to journalably mount a wheel and axle assembly; support means having a pivotal connection to one end of said carrier means and provided with an element slidably cooperable with the other end of the carrier means for supporting said carrier means for limited pivotal movement; a wedge means interposed between the support means and carrier means and having a slot guidably engaging said element; and means carried by the support means and connected to the wedge means for advancing and retracting the wedge means to raise and lower the wheel and axle assembly by pivotal movement of the carrier means.
